Primary Examiner — Rashida C. Walshon*(74) Attorney, Agent, or Firm* — Boudwin Intellectual Property; Daniel Boudwin(57) **CLAIM**

The ornamental design for a shoe cover, as shown and described.

DESCRIPTION

FIG. 1 shows a perspective view of a shoe cover showing my new design.

FIG. 2 shows a right side elevation view of the shoe cover.

FIG. 3 shows a left side elevation of the shoe cover.

FIG. 4 shows a front end elevation view of the shoe cover.

FIG. 5 shows a rear end elevation view of the shoe cover.

FIG. 6 shows a top plan view of the shoe cover; and,

FIG. 7 shows a bottom plan view of the shoe cover.

The broken lines shown in the drawings form no part of the claimed design.

1 Claim, 4 Drawing Sheets(56)
